THERAPEUTIC DEVICE

Filed Sept. 16, 1926

By Inventor,
John G. Purdie,
Trickey & DeBush,
Attorneys

UNITED STATES PATENT OFFICE

JOHN C. PURDIE, OF CHICAGO, ILLINOIS

THERAPEUTIC DEVICE

Application filed September 16, 1926. Serial No. 135,712.

My invention relates to therapeutic devices and has for its object the provision of a new and improved form and arrangement of parts in a device of this type for administering treatments by the use of oxygen together with water or some other liquid and preferably with the oxygen and water heated. It is the object of my invention to provide an improved form of means for delivering a stream 10 of oxygen and a suitable liquid upon the surface of a part being treated, and to provide such means in a form adapted for carrying off the liquid and the oxygen so as to avoid so far as possible any inconvenience to the 15 patient and to avoid any excessive amounts of oxygen in the air of the room where the treatments are being given.

It is another object of my invention to improve devices of this type in sundry details 20 hereinafter pointed out. The preferred means by which I have accomplished my several objects are illustrated in the drawing and are hereinafter specifically described. What I desire to cover by Letters Patent is 25 set forth in the claims.

The drawing is a central vertical section through my improved device, certain of the parts being broken away for clearness of illustration.

Referring to the drawing,—10 indicates a receptacle preferably in the form of a metal cylinder open at its upper end and provided with screw threads for receiving a closure head 11 also preferably of metal. The head 30 11 is provided with a transversely extending duct 12 into the end of which extends a nipple 13 upon which is mounted a rubber tube 14 through which oxygen is adapted to be fed under pressure from any suitable source. 35 Leading from the end portion of the duct 12, I have provided a piece of metal tubing 15 which extends downwardly from the head 11 for some little distance and is then turned backwardly upon itself for passage through another opening in the head 11 into communication with a chamber 16 in the head, such chamber 16 being provided by the use 40 of a plug 17 in the duct 12. The return portion of the tube 15 is bent in the form of a 45 coil, the coil portion being indicated by the numeral 18.

Extending into the receptacle 10 through an opening in the lower end thereof is a sleeve 19 closed at its upper end, such sleeve 50 being of a size such as to have a snug fit within the coil 18. The sleeve 19 is preferably soldered in position in the opening through the lower end of the receptacle 10. Within the sleeve 19, there is removably mounted an 55 electrical heating element 20 of any approved type, such heating element being mounted within a wooden sleeve 21 which is slidably mounted upon the lower end of the sleeve 19, the heating element 20 being electrically connected within the sleeve 21 with the wires of an electric cable 22 leading from any suitable 60 source of electrical energy, the arrangement being such that the sleeve 21 with the heating element 20 can be withdrawn from the 65 sleeve 19 when desired.

The head 11 is provided further with pieces 70 of tubing 23 and 24 opening into the upper end of the receptacle 10 at about the center of the upper end of the receptacle. The tube 75 23 communicates with the chamber 16 above described, while the tube 24 communicates with a chamber 25 separated from the chamber 16 by a partition 26. Within the chamber 25, there is mounted an ejector device 27 80 terminating in a nozzle 28 extending some little distance beyond the head 11. A tube 29 is mounted in the head 11 in communication with the opening 30 of the ejector 27, such tube 29 extending downwardly into the 85 receptacle 10 and having mounted upon its lower end a piece of rubber tubing 31 which is of a length adapted to extend substantially to the bottom of the receptacle, being provided at its lower end portion with a weight 90 32 which is provided for causing the tube to seek the lowest part of the receptacle 10 when the receptacle is placed in position on its side so as to keep the open end of the tube always in contact with the water contained in the receptacle. A very light coiled spring 33 is mounted upon the tube 31 for preventing the tube from becoming kinked. 95

At one side, the head 11 is provided with a screw threaded nipple 34 by which I re- 100

movably mount in position a cup-shaped shield 35 preferably formed of glass, such shield extending some little distance beyond the end of the nozzle 28 which is in centered position with respect to the shield 35. At its lower portion, in the position shown in the drawing, the shield 35 is provided with a nipple 36 secured in the wall of the shield and having mounted thereon a flexible tube 37 of any desired length, such tube 37 being connected at its other end with a receptacle 38, the arrangement being such that the gas and water delivered to the shield 35 through the nipple 28 as hereinafter described are adapted to escape through the tube 37 to the receptacle 38. A plug 39 is secured by means of screw threads in the upper end of the receptacle 38 for the purpose of emptying the receptacle. A flexible tube 40 is connected with the upper end of the receptacle 38 for carrying off the oxygen from the receptacle, the tube 40 leading preferably out of the room where the device is being used.

In use, the receptacle 10 is preferably filled with water of the desired temperature. The end of the shield 35 is then placed by the operator in contact with the surface of the body of a patient for a treatment and oxygen is admitted through the tube 14 in controlled amounts and under controlled pressures as may be desired. The oxygen passes downwardly through the tube 15 and upwardly through the coil 18, the oxygen in the passage through this tube being brought to substantially the same temperature as that of the water in the receptacle 10. The oxygen passes then from the chamber 16 to the body of the receptacle, and thence through the tube 24 and chamber 25 to the ejector 27 and through the nozzle 28. The oxygen passing through the ejector 27 causes a stream of the water to pass upwardly through the tube 31 and out through the nozzle 28 in the form of a spray with the oxygen, the water and the oxygen being delivered upon the surface being treated. As above explained, the water and oxygen after being forced into contact with the part being treated are caused to escape through the tube 37 to the receptacle 38, the oxygen passing out through the tube 40. By reason of having the tube 37 connected with the shield 35 at its lowermost point and at a point below the lowermost part of the front opening of the cup, the water is caused to run off without delay and is thus prevented from standing in contact with any part of the surface being treated. It thus is prevented from interfering with the treatment.

By making the tube 31 flexible so as to remain in contact with the water in the lowermost portion of the receptacle as the receptacle is shifted from one position to another, the device is suitable for use in a great

variety of positions to meet the convenience of the operator.

If it is desired that the water in the receptacle 10 be maintained at a steady heat, or if for any other reason it is desirable, electrical energy is to be fed to the heating unit 20 through the cable 22. The heat generated by the unit 20 serves to heat the water in the receptacle 10 and also to heat the oxygen passing through the coil 18.

While I prefer to employ the construction substantially as shown in my drawing and as above described, I do not wish to limit my invention to the form shown except so far as certain of the claims are specifically so limited, inasmuch as it is evident that changes might well be made in the form of the device without departing from my invention.

I claim:

1. A therapeutic device, comprising in combination a receptacle adapted to hold water, means for delivering oxygen under pressure to said receptacle above the water, a nozzle device, connections between the end of the nozzle and the upper end portion of the receptacle, a flexible tube connecting at one end with an intermediate portion of the nozzle and opening at its other end into said receptacle, a weight means for carrying the open end of the tube into the water in any position of the receptacle, and means for preventing the tube from doubling abruptly upon itself.

2. A therapeutic device, comprising in combination a receptacle adapted to hold water, a sleeve extending into said receptacle and closed at its inner end, means for conducting oxygen a plurality of times about said sleeve and for delivering it under pressure to said receptacle above the water, a nozzle communicating with said receptacle for delivering a stream of oxygen and water therefrom, and electrically operated heating means removably secured in said sleeve for heating both the water and the oxygen in the receptacle.

3. A therapeutic device, comprising in combination a receptacle adapted to hold water, a sleeve extending into said receptacle and closed at its inner end, means for applying heat to the interior of said sleeve for heating the contents of the receptacle, means for conducting oxygen under pressure about said sleeve in close proximity thereto, means for delivering the oxygen to the receptacle above the water therein, and a nozzle device communicating with said receptacle for delivering a stream of oxygen and water therefrom.

4. A therapeutic device, comprising in combination a receptacle adapted to hold water, a sleeve extending into said receptacle and closed at its inner end, means for applying heat to the interior of said sleeve for heating the contents of the receptacle, a tube in the form of a coil about said sleeve and com-

municating with the receptacle above the water therein for delivering oxygen under pressure thereto, and a nozzle device communicating with said receptacle for delivering a stream of oxygen and water therefrom.

5 5. A therapeutic device, comprising in combination a receptacle adapted to hold water, a head secured in position by screw threads for closing the upper end of the receptacle, a sleeve extending into the lower end portion of said receptacle and closed at its upper end, means for applying heat to the interior of said sleeve for heating the contents of the receptacle, a tube in the form of a coil mounted on the lower face of said head embracing said sleeve and opening into the upper end portion of the receptacle, means for delivering oxygen under pressure to said tube, and a nozzle device communicating with said receptacle for delivering a stream of oxygen and water therefrom.
